Des. 198,131
Patented May 5, 1964

198,131

ELECTRICAL OUTLET

Le Roy F. Radtke, Chicago, Ill., assignor to Ideal Industries, Inc., Sycamore, Ill., a corporation of Delaware

Filed Feb. 4, 1963, Ser. No. 73,416

Term of patent 14 years

(Cl. D26—1)

FIG.1.

FIG.2.

FIG.3.

FIG.4.

FIG.5.

FIGURE 1 is a front elevational view of an electrical outlet, showing my new design;

FIGURE 2 is a right end elevational view thereof;

FIGURE 3 is a rear elevational view thereof;

FIGURE 4 is a top plan view thereof; and

FIGURE 5 is a bottom plan view thereof.

I claim:

The ornamental design for an electrical outlet, as shown.
